(57) **CLAIM**

The ornamental design for two-piece hand guard for a rifle, as shown and described.

DESCRIPTION

FIG. 1 is a front/right side isometric view of the present invention;

FIG. 2 is a front elevational view of the invention of FIG. 1;
FIG. 3 is a rear elevational view of the invention of FIG. 1;
FIG. 4 is a right side elevational view of the invention of FIG. 1;

FIG. 5 is a left side elevational view of the invention of FIG. 1;

FIG. 6 is a top view of the invention of FIG. 1; and,
FIG. 7 is a bottom view of the invention of FIG. 1.

The broken line showing of aspects of the two-piece hand guard for a rifle is included for the purpose of illustrating environment and forms no part of the claimed design.
